UNITED STATES PATENT OFFICE.

ELMER F. FISHER, OF SPRINGFIELD, MASSACHUSETTS.

AIR AND GAS VALVE.

1,195,667.

Specification of Letters Patent. Patented Aug. 22, 1916.

Original application filed March 16, 1915, Serial No. 14,838. Divided and this application filed October 22, 1915. Serial No. 57,311.

To all whom it may concern:

Be it known that I, ELMER F. FISHER, a citizen of the United States of America, residing at Springfield, in the county of 5 Hampden and State of Massachusetts, have invented a new and useful Air and Gas Valve, of which the following is a specification, this application being a divisional part of an application filed by me in the United 10 States Patent Office, March 16, 1915, Serial No. 14,838, for Letters Patent on a heating No. 1195,667. appliance.

My invention relates to improvements in valves designed to admit both air and gas 15 to the burners of boilers of various types and other heaters, and consists of certain peculiar, automatic, air-controlled, air and gas valve members connected together, and arranged and adapted to admit a supply of 20 air and gas to the burner and to shut off such supply, together with such auxiliary and subsidiary parts and members as may be needed or desired in order to render the valve practicable and efficient in every respect, all as hereinafter set forth.

An object of my invention is to provide a valve, which is simple in construction and operation, for supplying air and gas in proper proportions and economically to a 25 burner.

A further object is to utilize the air supply with which to open the gas valve, or with which directly to control said valve.

This valve can be used to advantage with 30 a great variety of burners and therefore has a broad field of application, which is an important advantage. Said valve, furthermore, is susceptible of very close adjustment.

Other objects and advantages will appear in the course of the following description.

I attain the objects and secure the advantages of my invention by the means illustrated in the accompanying drawings, in 35 which—

Figure 1 is a vertical section through a valve or valve mechanism and connected parts and members wherein is embodied a practical form of my invention, the valve members being shown closed in full lines and open by dotted lines, and, Fig. 2, a side elevation of the gas valve.

Similar numerals designate similar parts throughout the several views.

Although this valve is particularly well

adapted for use in connection with tubular steam boilers for house-heating purposes, it is equally well adapted for use with hot-water heaters, hot-air furnaces, stoves, and other kinds of heaters, hence the scope of 60 said valve in the matter of practical application is in no sense limited by reason of the variations which exist in heaters and their grates. I have here represented the valve in connection with fragmentary parts of a tubular steam boiler and the grate therein.

It is to be understood that the air, which is admitted to this valve and by the latter to the heater, and which also is utilized for opening the gas valve member to admit the 70 gas with the air to said heater, is introduced under forced draft, any suitable well-known power-driven fan, pump, or suction device being employed to introduce such air under pressure. This air supply not only opens the 75 gas valve member, but also holds it open, and permits the same to close, and at the same time controls the air valve member by means of which the volume of air itself is controlled, as will presently appear.

In the first view a small portion of a tubular steam boiler is represented at 1, and a fragment of a gas burner at 2 with a perforated plate 3 beneath, a mixing chamber, wherin are commingled the gas and air to 80 be burned above said burner, being represented at 4.

A perforated, tubular, pilot-light burner 5 is set in the casing of the boiler 1, with the perforated portion just above the adjacent part of the burner 2, and opening outside of said casing. Normally a small flame or pilot-light is maintained by the burner 5 all the time, and the instant the burner 2 is supplied with fuel the latter is ignited from 90 said pilot-light, in the customary manner. A gas-supply pipe is represented at 6, and a small conduit 7 leads from that to the vicinity of the open outer end of the burner 5. The conduit 7 opens at the bottom adjacent 95 to the outer end of the burner 5, as shown at 8, there being sufficient space between the two members for the necessary amount of air to enter said burner with the gas from said conduit. As long as the flame is maintained 100 at the inner or perforated terminal of the burner 5, the fuel is supplied thereto, and no gas escapes on the way from the outlet 8 to said burner into the surrounding atmosphere. The conduit 7 is provided with a 110

valve 9 as usual. There is, of course, nothing new about the pilot-light.

A hollow elbow 10, constituting a primary mixing or fuel-supply chamber 11, opens at 5 one end into one side of the mixing chamber 4 in the bottom of the boiler 1, as represented at 12. A vertical gas-inlet member 13 is secured to the elbow 10, partly within and partly without the same, and into the open 10 end at the base of said elbow is screwed an air-inlet member which, in the present case, takes the form of a coupling 14. An air-supply pipe 15 has one end connected with the coupling 14 and the other end connected 15 with a suction or forced-draft generating element or device, such as the lower represented in the hereinbefore-mentioned application. The upper terminal of the coupling 14, inside, is made flaring, as shown at 16. 20 The gas-inlet member 13 has a valve-seat 17 at the upper end of an angular passage 18 in said member, such passage opening at the top through said valve-seat, and at the bottom laterally through one side of said 25 member into the fuel-supply chamber 11. A coupling 19 connects the member 13 with the gas-supply pipe 6. A valve 20 is provided for the valve-seat 17, such valve opening upwardly into the coupling 19. The 30 valve 20 is provided on the underside with a hollow open-bottom guide 21 and a long stem 22. The guide 21 has a sliding fit in the vertical part of the passage 18 and serves to center the valve 20, and said guide is provided in the sides directly under said valve 35 with one or more openings 23, through which the gas passes from the coupling 19 when said valve is raised from its seat. The valve stem 22 passes downward from the 40 valve 20 through the axial centers of the guide 21, the vertical part of the passage 18, and the base of the member 13, into the coupling 14, said stem being adapted to slide freely in the vertical passage provided for 45 it in said base.

The parts and members are so arranged that the stem or rod 22 is in line with the axial center of the coupling 14. The rod 22 is provided with a stop to limit the upward 50 rise thereof and of the valve 20, such stop here consisting of a nut 24 screwed on to said rod below the base of the member. When the valve 20 is opened the nut or stop 55 24 comes into contact with the member 13, and so limits the upward movement of the parts, and serves to determine the amount of gas admitted through the openings 23, provided such stop be so positioned on the stem 22 as to contact with said member before 60 said openings are carried entirely clear of the valve-seat 17. The stop 24 is adjustable on the screw-threaded portion of the valve stem. A check-nut 25 is provided on the rod 22 for the stop 24. The stem 22 is provided with an air valve or air-valve member 65

of the loose piston type, such valve here being in the form of a disk 26 screwed on to that portion of said stem which extends into the coupling 14. The disk or air valve member 26, like the stop 24, is adjustable on the 70 valve stem, and a check-nut 27 is provided on said stem for said valve. The diameter of the valve member 26 should be a little less than the interior diameter, below the flaring parts 16, of the coupling 14.

The air injected into the pipe 15 and the coupling 14, by being blown or sucked in by any suitable means and in any suitable manner, as hereinbefore stated, comes into contact with the valve member 26, raises the 80 same, and so causes the gas-valve 20 to be lifted, through the medium of the stem 22, from the valve-seat 17, and gas to be admitted from the coupling 19 to the chamber 11, through the openings 23, guide 21, and passage 18. Thus both gas and air are admitted to the chamber 11 at the same time. The two elements commingle in the chamber 11 and immediately pass through the outlet 90 into the large mixing chamber 4 below the plate 3 and the burner 2. As soon as the forced draft through the pipe 15 ceases the valve members drop by gravity, the valve 20 returning to its seat and cutting off completely the flow of gas to the chamber 95 11.

The supply of air to the chamber 11 may be increased by screwing down the coupling 14 so as to increase the open space, between 100 the valve member 26 and the flaring walls 16, when said member is raised by the air, and said supply may be decreased by screwing up said coupling so as to decrease such space when said valve is raised. Likewise, by locating the member 26 higher on the 105 stem 22 the volume of the air supply to the chamber 11 is increased, and by locating said member lower on said stem such volume is decreased. Thus I provide a double adjustment or two adjustments for regulating 110 the air supply.

The operation as a whole of the valve is described as follows: As a preliminary the valve 9 is opened and the gas or gas and air mixture is ignited at the burner 5. This pilot-light burns continuously until such time as the valve 9 may again be closed. Air is admitted to and forced through the pipe 15 and the coupling 14 into the chamber 11. In entering the chamber 11 the air encounters the disk 26 and elevates said disk and with it the rod 22 and the valve 20 into the position indicated by the dotted lines in Fig. 1. When the valve 20 is raised from its seat, the way to the chamber 11 is opened, through the openings 23, the guide 21, and the passage 18, so that gas immediately passes from the coupling 19 to said chamber. In the chamber 11 the air and gas commingle and pass into the chain- 120 125 130

ber 4 wherein they are still more thoroughly mixed. The fuel mixture in the chamber 4 rises through the plate openings 28 to the burner 2, and then rises through the 5 burner orifices 29. As soon as the fuel mixture reaches the top of the burner 2 it is ignited by the pilot-light and burns in the usual manner. In due time the temperature of the heater 1 rises to a point where 10 action is brought about, as through the medium of the circuit-breaking mechanism set forth in the aforesaid application, which cuts off, diminishes, or discontinues the force that supplies the air to the pipe 15, so there 15 is little or no pressure beneath the disk 26, and said disk and connected parts drop and shut off the gas from the chamber 11. Without further gas and air supply for the burner 2, combustion above or at such burner 20 must and does cease. There is now no consumption of gas except the small amount consumed by the pilot-light.

Without the heat at the burner 2 the temperature of the boiler falls, and such temperature continues to fall until the suction or forced-draft, that is, the air pressure in the pipe 15, is reestablished, when the disk 26 is again raised and the valve member 20 reopened, resulting in the delivery to the 30 burner of a further supply of gas and air. This cycle of events may and in practice will be repeated indefinitely.

When the valve is used in connection 35 with an oil-burning appliance the air is sucked into a chamber such as the chamber 11, instead of being blown into the same.

Various changes or modifications in the 40 shape, size, arrangement, and construction of some or all of the parts of the valve may be made without departing from the nature of the invention.

What I claim as my invention, and desire to secure by Letters Patent is—

1. In an air and gas valve, a hollow member 45 having an air inlet and a gas inlet which are remote from each other, and also having an air and gas outlet, said gas inlet having a valve-seat, and said air and gas outlet being located approximately intermediate of said air inlet and said valve-seat, an unattached valve for said seat, said valve being arranged to open against the gas pressure, and provided with a stem which extends into said air inlet, and a valve member 50 on said stem in said air inlet and adapted to operate freely therein, said valve member being unattached except to said stem, and the arrangement of parts being such that air, in passing into and through the inlet therefor, impinges directly on said valve member, and moves the same with said stem and gas valve, axially, to make a passage for itself past said valve member and open said gas valve.

2. In an air and gas valve, a hollow mem-

ber having an air inlet provided with an adjustable flaring member, and also having a gas inlet with a valve-seat, and an air and gas outlet located approximately intermediate of said air inlet and said valve-seat, 70 said inlets being remote from each other, an unattached gas valve for said valve-seat, said valve being arranged to open against the gas pressure, and provided with a stem which extends into said flaring member, and 75 a valve member on said stem in said flaring member, said valve member being unattached except to said stem, and the arrangement of parts being such that air, in passing into and through said flaring member, is 80 regulated in volume by the position of the latter, and impinges directly on said valve member, and moves the same, with said stem and gas valve, axially, to make a passage for itself past said valve member and open said 85 gas valve.

3. In an air and gas valve, a hollow member having a flaring air inlet and a gas inlet which are remote from each other, and also having an air and gas outlet, said gas 90 inlet having a valve-seat, and said air and gas outlet being located approximately intermediate of said air inlet and said valve-seat, an unattached valve for said seat, said valve being arranged to open against the gas pressure, and provided with a stem which extends into said air inlet beyond the flaring portion thereof, a valve member on said stem in said air inlet and adapted to operate freely therein, said valve member being unattached except to said stem, and means to adjust said valve member on said stem, the arrangement of parts being such that air, in passing into and through the inlet therefor, is regulated by the position of said valve 95 member on said stem, and impinges directly on said valve member, and moves the same, with said stem and gas valve, axially, to make a passage for itself past said valve member and open said gas valve.

4. In an air and gas valve, a hollow member having an air inlet and an air and gas outlet, a gas-inlet member provided with a valve-seat, and opening outside through said seat and inside into said hollow member, at a point remote from said air inlet, said air and gas outlet in said hollow member being located approximately intermediate of said air inlet and said valve-seat, an unattached valve for said seat, said valve being arranged 115 to open against the gas pressure, and provided with a stem which extends through said gas-inlet member into said air inlet, a valve member on said stem in said air inlet and adapted to operate freely therein, said valve member being unattached except to said stem, and a stop on said stem in position to contact with said gas-inlet member and limit the valve-opening movement, said 120 gas valve and valve member being moved 125 130

axially, by the air in passing through the inlet therefor and impinging directly on said valve member, to make a passage for said air past said valve member and open said valve-seat.

5. In an air and gas valve, a hollow member having an air inlet and an air and gas outlet, a gas-inlet member having a passage therein and provided with a valve-seat, and
10 opening outside through said seat and inside into said hollow member at a point remote from said air inlet, said air and gas outlet in said hollow member being located approximately intermediate of said air inlet
15 and said valve-seat, an unattached valve for said seat, said valve being arranged to open against the gas pressure, and provided with an apertured guide to slide in said passage, and with a stem which extends through said
20 gas-inlet member, without obstructing the gas-way through said guide and passage, into said air inlet, and a valve member on said stem in said air inlet and adapted to operate freely therein, said valve member being un-
25 attached except to said stem, and said gas valve and valve member being moved axially, by the air in passing through the inlet therefor and impinging directly on said valve member, to make a passage for said

air past said valve member and open said valve-seat.

6. The combination with a heater provided with a burner, and having a mixing chamber under said burner, of an air and gas valve comprising a hollow member having an air inlet and a gas inlet which are remote from each other, the latter having a valve-seat, and said member opening at a point approximately intermediate of said air inlet and said valve-seat into said mixing chamber, an unattached valve for said seat, said valve being arranged to open against the gas pressure, and provided with a stem which extends into said air inlet, and a valve member on said stem in said inlet and adapted to operate freely therein, said valve member being unattached except to said stem, and the arrangement of parts being such that the air, in passing through the inlet therefor, impinges directly on said valve member, and moves the same, with said stem and gas valve, axially, to make a passage for itself past said valve member and open said gas valve.
